[57] CLAIM

The ornamental design for a key holder, as shown and described.

DESCRIPTION

FIG. 1 is a perspective view of a key holder showing my new design;

FIG. 2 is a side elevational view, showing one of two identical sides thereof;

FIG. 3 is a plan view;

FIG. 4 is a side elevational view, showing one of two identical sides thereof;

FIG. 5 is a plan view;

FIG. 6 is a perspective view shown in exploded condition;

FIG. 7 is a perspective view of a key holder showing a second embodiment of my new design in exploded condition;

FIG. 8 is a side elevational view of a key holder showing a third embodiment of my new design in assembled condition;

FIG. 9 is a side elevational view, showing one of two identical sides thereof;

FIG. 10 is a plan view thereof;

FIG. 11 is a plan view thereof;

FIG. 12 is a perspective view thereof, shown in exploded condition;

FIG. 13 is a perspective view of a key holder showing a forth embodiment of my new design shown in exploded condition;

FIG. 14 is a perspective view of a key holder showing a fifth embodiment of my new design shown in assembled condition;

FIG. 15 is a perspective view of a key holder showing a sixth embodiment of my new design shown in exploded condition;

FIG. 16 is a perspective view of FIG. 14, shown in exploded condition;

FIG. 17 is a elevational view thereof;

FIG. 18 is a plan view thereof; and

FIG. 19 is a plan view thereof.
